UNITED STATES PATENT OFFICE

VERNON G. LEACH, OF CHICAGO, ILLINOIS, ASSIGNOR TO MODERN COAL BURNER COMPANY, OF CHICAGO, ILLINOIS, A CORPORATION OF ILLINOIS

MECHANICAL UNDERFEED STOKER

Application filed August 24, 1929. Serial No. 388,065.

This invention relates to improvements in mechanical underfeed stokers and more particularly in the construction of the tuyère blocks.

5 It is an object of this invention to provide an improved construction of tuyère blocks for use in mechanical underfeed stokers and adapted to provide an efficient distribution of air to the fire bed.

10 It is a further important object of this invention to provide a tuyère block of such construction that there is a proportionate distribution of air even should the ends of the tuyère block become burned off for a considerable distance.

15 Other and further important objects of this invention will be apparent from the disclosures in the specification and the accompanying drawings.

20 This invention (in a preferred form) is illustrated in the drawings and hereinafter more fully described.

On the drawings:

25 Figure 1 is a transverse sectional view of a furnace setting illustrating the arrangement of tuyère blocks embodying the principles of this invention.

Figure 2 is a top plan view of the mechanical underfeed stoker unit.

30 Figure 3 is an enlarged side elevational view of a tuyère block.

Figure 4 is a bottom plan view of the same.

Figure 5 is an end elevational view of a pair of tuyère blocks.

35 Figure 6 is a sectional view taken substantially on line VI—VI of Figure 3.

As shown on the drawings:

The reference numeral 1 indicates generally a furnace housing comprising lower walls

40 2 of masonry and upper side walls 3. Partly within said housing 1 is mounted a mechanical underfeed stoker indicated as a whole by the reference numeral 4. Said

45 stoker 4 comprises a hopper 5 into which the coal or other fuel is charged and a worm conveyor 6 extending from the bottom of said hopper 5 through a conduit 7 into a retort 8.

The screw conveyor 6 is adapted to be driven

50 by any suitable means, such as the motor 9

and reducing mechanism 10, for conveying the crushed coal into the retort 8.

Said retort 8 comprises a casting formed with side walls 11 and 12 provided with parallel, flanged upper edges 13 and 14, respectively.

Tuyère blocks 15 of my invention are adapted to be mounted upon the upper flanged edges 13 and 14 and for this purpose are provided with a lower lug 16 in the form 60 of a hook for detachably engaging said flanged edges 13 and 14. The outer base portions of said tuyère blocks 15 rest upon and are supported by angle irons 17 or other suitable supporting means. A groove 50 is 65 formed transversely of each of said tuyère outer base portions to receive cement or the like for forming an air-tight joint with the angle iron support, should it be desirable to put an air seal from the angle iron 17 down 70 to the floor. Each of said tuyère blocks 15 is further formed with a groove 18 extending transversely along its outer upper face 75 for receiving the downturned lateral edge 19 of a dead plate 20. Other dead plates 21 and 22 are suitably associated therewith and mounted upon the masonry walls 2 to form a relatively air-tight supporting surface for the burning coal from which the clinkers and ash may be removed.

80 A front plow plate 23 and a rear plow plate 24 preferably formed in sections, form the end walls of the built-up retort.

As thus illustrated in Figures 3 to 6 inclusive, each of the tuyère blocks 15 is formed of a single casting having an intermediate vertical web 25, a vertical inner edge 26 flanged for a portion of its height as at 27 and outwardly and downwardly sloping flanged edge 28, the flanged portions in every case extending equally on each side of the intermediate web portion 25.

85 A plurality of ribs 29 and 30 are formed on said intermediate web portion 25 to extend from the inner upper edge 26 to the near outer lower portion of said web 25. Said ribs 29 and 30 are symmetrically formed on each side of the web 25. Said ribs 29 and 30, furthermore, are equally spaced from each other and from the top flange 28 and the top 90 95 100

of the lower inner edge flange 27 to provide substantially uniform grooves or passages 31, 32 and 33 along the inner edge 26 of said web 25, said grooves gradually diverging as they 5 extend outwardly and downwardly to the end of said ribs 29 and 30. The outer ends of said ribs 29 and 30 are tapered as at 34 and 35, respectively, to reduce resistance to the flow of air through the grooves or channels 10 31, 32 and 33.

In the event that it is desired to make a two-opening tuyère rather than a three opening, as shown, rib 30 may be omitted entirely and rib 29 spaced equally from the top flange 15 28 and the top of the inner edge flange 27. In order to prevent the escape of air between abutting tuyère blocks below the openings 38, the lateral edges of the flanges 27 are provided with grooves 46 adapted to be filled 20 with a suitable cement and thus render the joints air tight.

When the tuyère blocks are aligned in position, as shown in Figure 5, corresponding adjacent grooves 31, 32 and 33 in adjacent 25 tuyère blocks form passages 36, 37 and 38, respectively, of generally rectangular cross section for the flow of air into the fuel bed.

As arranged above the side walls of the retort 8, the vertical inner edges 26 of the tuyère 30 blocks including their lower flanged inner edges 27, form a vertical continuation of the side walls 11 and 12 of said retort. The mass of coals accordingly builds up between the 35 vertical walls 39 and 40 formed by the inner faces of said tuyère blocks and overflows down over the outwardly and downwardly inclined walls 41 and 41' formed by the abutting flanged edges 28 of said tuyère blocks. Air is supplied in the usual manner underneath the dead plates and flows upwardly 40 through the passages 31, 32 and 33 between the tuyère blocks. Because of the tapered formation of the ribs 29 and 30 and the general curvature and arrangement of said ribs and the flanged edges 27 and 28, little resistance 45 is offered to the flow of air through said tuyère blocks into the fuel bed. The arrangement and shape of the tuyère blocks are such that the hot zone of the fuel bed does not extend down into the retort proper, so that the body of the retort is below the hot zone and is not subject to such high temperatures as would cause expansion strains. Also, the ribs and fins of the tuyère blocks 50 serve as heat conductors to dissipate the heat into the main cooling web, the web 25.

Consequently there is little tendency for the tuyère blocks to become over heated, but it should be noted that if the top front faces 60 of the tuyère blocks should become burned away after long continued use, the relative size and spacing of the air passages 36, 37, and 38 remain substantially constant owing to the fact that the upper curved portions 42, 43 and 44 of the flanges 28 and ribs 29 and 30, 65

respectively, are formed along substantially concentric arcs. Even the upper edge of the front flange 27 is curved as at 45 in conformity with the curves 42, 43 and 44.

The cement seals between the tuyère blocks themselves and between the tuyère blocks and supporting surfaces eliminate the possibility of air leaking into the fuel bed within the built up retort so that all of the air is delivered through the passages 36, 37 and 38, 75 well up toward the top of the tuyère blocks, with the result that the fire line is kept above the top of the retort proper.

There is thus provided a substantially radial distribution of air throughout the fuel bed. The backward slope of the tuyère blocks is such that the fuel bed builds up above the retort and tuyères in the form of a fairly flat, curved mound, all outside portions of which are substantially equi-distant from the air inlets, with the result that the air does not tend to follow localized channels but is evenly distributed throughout the fuel bed.

The downward and backward slope of the tuyère blocks aids to carry the slag down onto the dead plates, from which it is drawn or pulled out of the furnace.

Renewal of a tuyère block is facilitated by the arrangement and construction of tuyères and dead plates in that it is only necessary in order to remove a burned out tuyère to lift out one of the dead plates 20.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. A tuyère block for a single-retort stoker having parallel spaced walls, said block being a substantially quadrantal member having a web with a lower edge adapted to rest on a wall of the stoker, a vertical inner face including a spacing flange extending from the lower edge of the web to a point more than half way up the inner edge of said web, a curved flanged edge defining the convex edge of the block and extending from the top of the inner edge of the web to the lower edge of the web, and spaced inwardly converging curved ribs on the web between the flange on the inner edge of the web and the said curved flanged edge and having ends terminating at the inner edge of the web in spaced apart relation to said flanges.

2. In combination, in a single-retort stoker, a supporting wall, a substantially quadrantal tuyère block having a web with a base edge on the wall, an inner edge having a flanged portion extending from said base edge for a substantial distance along said inner edge, a flanged curved edge defining the

convex edge of the block and extending between the top of the inner edge and the base edge and forming a part of the base edge, said flanged curved edge having a transversely extending groove near the lower end thereof, and means overlying a portion of said tuyère block and entered in said groove to hold said block in clamped relation seated on the wall.

10 3. A tuyère block for a single-retort furnace stoker having a wall, said block being substantially quadrantal in shape, and having a web with a flanged curved edge defining the convex edge of the block and extending from its base edge to the top of its vertical inner edge, the said block being adapted to be seated on its base edge on a wall of the stoker, a flanged edge extending from the base of the web along its vertical inner edge 15 for a distance more than half way along the inner edge, spaced and inwardly converging curved ribs on the web between the flange on the vertical inner edge and the curved edge, said ribs extending from the vertical inner edge of the web downwardly and outwardly, and having a depth substantially equal to that of the curved flange edge and being spaced apart a distance substantially equal to their rib depth for a portion of their 20 length adjacent the vertical inner edge so that they define discharge orifices with adjacent blocks of substantially undiminished area until a substantial portion of the inner vertical edge of the web has been burned 25 away.

4. A tuyère block for a single-retort stoker, having a wall capped by an angle-iron and having dead plates on the wall, said block being substantially quadrantal in shape and 30 having a web with a base edge for seating on the wall and a hook projecting below said base edge adapted to engage an angle-iron on the wall, the said web also having a flanged curved edge defining the convex edge 35 of the block and extending from its vertical inner edge to its base edge and forming a part of the latter edge, the said curved edge having a recess formed therein near its end adjacent the base edge of the web adapted 40 to receive a portion of a dead plate to hold the block clamped seated on the wall of the retort.

5. A tuyère block for a single-retort stoker having a wall with a dead plate and an angle iron thereon, said block being substantially quadrantal in shape and having a web with a base edge for seating on the wall, an integral hook projecting downwardly from the base edge adapted to engage an angle iron, the said web having a flanged curved edge defining the convex edge of the block and extending between the top of its inner vertical edge and its base edge, said curved 60 flanged edge being reversely directed at its

lower end to provide an outwardly and upwardly extending toe adapted to engage a dead plate.

In testimony whereof I have hereunto subscribed my name at Chicago, Cook County, Illinois.
